ROTARY COCOON FIBER FEEDING APPARATUS

Saburo Minorikawa, Koishikawaku, Tokyo, Japan, assignor of one-half to Katakura Seishi Boseki Kabushiki Kaisha, Kyobashi, Kyobashiku, Tokyo, Japan

Application December 29, 1938, Serial No. 248,350

4 Claims. (Cl. 19—3)

This invention relates to improvements in a rotary cocoon filament feeding apparatus.

The object of the invention is to provide an apparatus of the above character of improved and simplified construction in which the parts may be readily removed and replaced in case of damage thereto.

5 The accompanying drawing shows one example of the cocoon fiber feeding apparatus according to the present invention.

Fig. 1 is a sectional elevation.

Fig. 2 is a side view.

Fig. 3 is a section through line 3—3 in Fig. 2.

Fig. 4 is a sectional view through the rotary drum showing the embracing bars.

Fig. 5 is a plan showing the bar when detached.

Fig. 6 is an elevation of the cylindrical axle for passing fibers.

Fig. 7 is an elevation of the flanged body.

20 Fig. 8 shows an elevation of the revolving drum.

Detailed explanations of the invention

Referring to the drawing; near the front end 25 of base plate 1, the upper portion of a fiber passage pipe axle 2 is threaded therein. The pipe axle 2 is fixed in suspended position, being held by nut 3.

A fiber passage hole 4 is bored axially through 30 the axle and in the lower portion of the fiber passage hole 4, female screw threads are provided.

A flanged body 6 with fiber passage hole 5, is provided with male screw threads cut on the 35 upper portion, which fit into the female threads in the lower portion of the hole 4 mentioned above.

A rotary drum 7 loosely fits on the pipe axle 2 and its lower cylindrical portion is made to revolve round easily, being held by the flanged body 6.

40 A V shaped channel 8 is provided in the drum 7 and in the channel thus provided, several water holes 9 are bored and connect to the clearance space 10 in the bore of the drum 7.

45 Drum 7 is made of plastic materials such as Bakelite and the lower portion has the form of a cylindrical body 11. Surrounding the cylindrical body 11, a circular groove 12 is cut around to allow embracing bars 13 and 14 to fit therein, so as to be placed or replaced easily. The metallic embracing bars are curved in their middle portions 15 so that they can embrace the cylindrical body 11; the straight portions are held together by soldering or other suitable means.

Resiliency is given to the middle portions of the bars 13 and 14.

An endless transmission belt 16 is engaged in the V shaped channel 8 of the drum 7, by means of which the drum is driven.

5 The transmission belt 16 is constantly moistened on its surface by means of feed water and the water thus carried to the channel 8 and water holes 9 passes into the clearance space 10.

The fiber passage pipe axle 2 is thus water 10 lubricated and at the same time the passage of transmission belt is made easy and smooth.

The embracing bars 13 and 14 can be simply and easily fitted in position by merely springing the curved portions apart. In case the bars are 15 damaged, they can thus be easily replaced by spare ones. Therefore the disadvantage of entirely replacing the apparatus in case of a partial damage, is dispensed with.

The flanged body with fiber passage 5, is usually 20 a portion easily damaged during the reeling operation but as this is simply screw connected in this case, it can be easily taken off.

Even in case the revolving drum is damaged, the drum can be easily taken off by first un- 25 screwing and removing the flanged body 6.

Thus the useless labor and expense of removing the whole device from the base plate, is also dispensed with. Thus according to the present invention, the parts composing the apparatus are 30 separately formed and arranged so that they can be easily placed or replaced and therefore in case of transporting the apparatus, identical parts can be assembled and packed together and in case of transports on large scale, the pack- 35 age volumes and expenses may be greatly saved.

Having thus described my invention, what I claim as new, and desire to secure by Letters Patent of the United States of America is:

1. A rotary fiber feeding apparatus comprising 40 a base plate, a fiber passage axle detachably supported by said base plate, a drum rotatable on said axle, said axle having an axial passage extending throughout the entire length thereof, said drum being provided with a peripheral channel for receiving a driving belt and holes formed in the bottom of said channel and extending to the interior of the drum.

2. A rotary fiber feeding apparatus comprising 45 a base plate, a fiber passage axle detachably supported by said base plate, a drum rotatable on said axle, said axle having an axial passage extending throughout the entire length thereof, a groove in said drum and bars resiliently embracing said groove.

3. A rotary fiber feeding apparatus comprising a base plate, a fiber passage axle detachably supported by said base plate, a drum rotatable on said axle, said axle having an axial passage extending throughout the entire length thereof, a groove in said drum and bars detachably mounted in said groove, said bars being resilient and adapted to be sprung apart to enable detachment and removal to and from said drum.

4. A rotary fiber feeding apparatus as claimed in claim 2 characterized in that said bars are formed of resilient material and have the medial portions thereof curved to embrace the groove in said drum and have the ends thereof connected together whereby said medial portions may be sprung apart. 5

SABURO MINORIKAWA.
